UNITED STATES PATENT OFFICE

FRANK G. FREESE, OF ALDAN, PENNSYLVANIA

RAIL LOCK

Application filed July 30, 1929. Serial No. 382,096.

My invention relates to means for anchoring or locking railroad rails against movement, particularly the longitudinal movement known as creeping.

5 In carrying out my invention I propose to associate with the usual spikes which are employed to hold the rails to the ties, anchoring or locking means which overlie the base flanges of the rail and are held in proper position by the spikes; one of such locking devices being associated with each spike.

My improved anchoring means comprises a member in the form of what may be termed a yoke washer, having a portion to overlie 15 the base flange of the rail beneath the head of the spike and a pair of laterally disposed depending portions, one of which lies at each side of the spike. The notch or recess of such yoke washer is of such dimensions that the 20 spike may bear against the edge of the base flange of the rail in the usual manner as well as against the locking member.

In order that my improved yoke washer may serve as anchoring or locking means for 25 the rails the inner surface of the same, designed for contact with the base flange of the rail, is provided with spurs or teeth which may be forced into the metal of the rail base by the pressure of the spike when setting the 30 same in place.

These and other features of my invention are more fully described hereinafter; reference being had to the accompanying drawings, in which:

35 Figure 1 is a plan view of part of a railroad track structure showing rail locks or anchors within the scope of my invention.

Fig. 2 is an elevation of the structure shown in Fig. 1; the rail being shown in section.

40 Fig. 3 is a perspective view of my improved rail lock.

Fig. 4 is a front elevation of the same.

Fig. 5 is an inverted plan view illustrating the character of the surface contacting with 45 the base flange of the rail, and

Figs. 6 and 7 are enlarged sectional views illustrating details of my invention.

My improved lock or anchoring structure may be employed with or without a tie plate. 50 In the present instance it is shown in connec-

tion with the spikes holding down a rail mounted upon a tie plate interposed between the rail and the tie. The rail is indicated at 1, the tie plate at 2, tie at 3 and the spikes at 4. In the present instance, I have shown a tie plate arranged for the reception of two spikes, one on each side of the base flange 1^a of the rail, but it will be understood that a greater number of spikes may be employed as practice may require or determine.

The spikes are so associated with the base flange of the rail as to provide contact of their shanks with the edges of these flanges; such contact being usual to prevent lateral displacement of the rail after it has been 55 spiked to the tie.

It is well known, of course, that rails tend to creep, particularly when traffic is moving in one direction. For the purpose of locking the rails to the tie plates and/or ties and to prevent the rail moving longitudinally relatively to the tie, I provide a rail lock in the form of a half washer or yoke member 5 which is so shaped as to provide a portion 5^a that may be placed under the head of the 60 spike, with depending portions 5^b lying against the edge of the base flange 1^a of the rail on opposite sides of the shank of the spike. The under side of this washer or yoke member is provided with spurs, teeth or other 65 engaging members 5^c designed to bite into the rail when the spike is driven home, thereby providing anchorage between the rail and the spike. By preference these spurs or teeth extend in opposite directions from the centre 70 of the under side of the portion 5^a of the locking member, as clearly shown in Fig. 6.

That portion of my improved rail lock element which underlies the head of the spike may be slightly arched as clearly indicated in Fig. 4, so that the opposite edges of such portion of the lock element will engage first with the upper surface of the base flange of the rail; the other portion of the under surface provided with the engaging teeth or 75 spurs making contact with the rail as the spike is driven home. In addition, the inner faces of the depending portions of the lock member are provided with spurs or teeth on 80 the surface contacting with the edge of the 85 rail.

base flange of the rail and as the spike engages the upper portion of this lock member and the web of the same, as clearly shown in Fig. 7, it will tend to push these portions against such base flange.

In use, the spike can be driven within approximately one-half inch of the rail flange and then the lock member may be placed under the head of the spike. Then by driving the spike all the way down, the lock member will be forced into holding engagement with the rail. As the lock member is confined between the head of the spike and the rail, the latter is held against longitudinal movement in either direction and the lock member is held against movement by reason of the fact that the depending portions 5^b of such lock member are disposed on both sides of the shank of the spike beneath the head of the latter.

In lieu of the individual spurs or teeth shown as struck up from the under surface of the lock member I may provide the same with serrations that will form substantially continuous teeth to bite into the base flange of the rail when the spike is driven home.

I claim:

1. The combination with a railroad rail, a tie, and a spike entering said tie for holding the rail thereto, of a locking member arranged to underlie a portion of the head of the spike and be retained thereby against longitudinal movement; said locking member having a portion disposed on each side of the spike for biting engagement with the rail to prevent movement of the latter when said locking member is held in place by the spike.

2. The combination with a railroad rail, a tie, and a spike entering said tie for holding the rail thereto, of a locking member arranged to underlie a portion of the head of the spike and be retained thereby against longitudinal movement; said locking member having spurs or teeth for biting engagement with the rail to prevent movement of the same when held in place by the spike.

3. The combination with a railroad rail, a tie, and a spike entering said tie for holding the rail thereto, of a notched locking member underlying a portion of the head of the spike and retained thereby against longitudinal movement; said locking member having spurs or teeth adapted to enter the rail and prevent movement of the same when held in place by the spike.

4. The combination with a railroad rail, a tie supporting the same, and a spike securing said rail to the tie, of a locking member having a portion underlying a portion of the head of the spike and depending portions disposed on opposite sides of the spike adapted to engage the edge of the rail flange; said locking member having spurs or teeth means on its under surface and being held in contact with the rail by the spike.

5. The combination with a railroad rail, a tie supporting the same, and a spike securing said rail to the tie, of a locking member having an arched portion underlying a portion of the head of the spike and depending portions disposed on opposite sides of the spike adapted to engage the edge of the rail flange; said locking member being held in contact with the rail by the spike and having spurs or teeth on its entire rail-engaging surface which are brought into action when retained in place by the spike.

6. As a new article of manufacture, a rail lock comprising a yoke washer to be held down by a spike and having an arched portion adapted to underlie the spike head; said arched portion having engaging members to hold a rail against longitudinal movement.

7. As a new article of manufacture, a rail lock comprising a yoke washer to be held down by a spike and having spurs or teeth disposed right and left with respect to the centre of the said lock so as to hold a rail against any tendency to move or creep in either direction.

In witness whereof I have signed this specification.

FRANK G. FREESE.
